COCKING MECHANISM FOR BREECH LOADING FIREARM

Luigi Piccolo, Milan, Italy

Application December 21, 1956, Serial No. 629,875

Claims priority, application Italy June 13, 1956

5 Claims. (Cl. 42—43)

Cocking mechanisms of breech-loading guns with moving breech closure operated by the breech rotation movements are known.

However they have all the disadvantage of requiring an excessive number of mechanically weak portions which make the operation thereof difficult and not sure and increase their manufacture costs. In order to overcome this disadvantage the present invention provides a novel cocking mechanism represented by way of example in the attached drawings, wherein:

Fig. 1 is a plan view of a breech according to the invention.

Fig. 2 is a side view, partly in section, of the firearm portion containing the mechanism of the present invention;

Fig. 3 is a cross-section along line 3—3 of Fig. 2;

Figs. 4, 5, 6 are diagrammatic views of a detail of the mechanism in three different positions;

Fig. 7 is a side view partly in section like Fig. 2 of the mechanism according to another embodiment.

As the drawing shows, the cocking mechanism, object of the invention, is substantially constituted by a hollow tubular body 1, provided at its closed front end with a lateral guide groove 2 and at the rear end with two small ears 3 being crossed by a pivot 4. A helical striking spring 5 is contained in tubular member 1, wherein a rod 6 slidable along the axis of the spring-holder member 1 is located. The rear end of the rod 6 is shaped as a piston with a hemispheric recess and therein is seated for turning movement a lug 7 of a triangularly slotted control member 8, another lug 9 of which is in turn articulated to the striking hammer 10, which rotates around the pivot 11.

The barrel-carrying breech piece 31 turns around a pivot 12 on the rear breech piece 30, and another pivot 13 is located in the groove 2 and fixed on the barrel-carrying breech piece 31. The hammer 10 is retained in cocked position by the point 15 of a sear lever 14 loaded by a spring 16, resting on the pivot 17, which forces sear lever 14 against hammer 10. Sear 14 is released by trigger 25, 26 urging portion 26a against arm 14a of sear 14. A safety catch 27 cooperates with trigger 25, 26.

In the Figs. 2, 3 is represented a striker point 18 guided by a cylindrical head 19 integrally connected thereto by a bracket 20 which ensures a regular sliding and furthermore an exact striking in spite of the head and striker point being located in two different planes. The weapon partly represented in Fig. 2 is a gun provided with two superposed barrels 31a shown in closed position after release of the right hammer (lower barrel). Fig. 3 shows the striker means 18, 19a, 20a for the second barrel and the members 3, 4 and 8 associated with the second barrel.

Figs. 3 and 4 represent the mechanism in the same position.

The very simple operation is evident with reference to Figs. 5, 6.

When the weapon is opened after release of hammer

10, by rotating the moving breech piece 30 (see also Fig. 1) around the pivot 12, the pivot 13 carries forward the tubular spring-holder member 1 and consequently the pivot 4 and the triangularly slotted member 8, the head 9 of which rotates hammer 10 into cocked position, wherein it is retained, as above mentioned, by the catch lever 14, 15 under action of spring 16. At the same time, due to the displacement of parts 5, 7, 9, and 10 with regard to the pivot 4, member 8 turns and its bearing point on the pivot 4 moves from the upper apex to the front lower apex of the triangular slot, see Fig. 7. Upon closing of the weapon, the spring-holder member 1 goes back, being driven by the pivot 13 sliding in the groove 2 and the spring 5 is compressed. Member 8 remains stationary and so does also hammer 10, being now under tension, but the bearing of pivot 4 moves in the triangular slot of member 8 from the front lower apex to the rear apex (see Figs. 5 and 6). Lastly upon release of sear lever 14 by means of the trigger 25, 26 overcoming the force of the small spring 16 bearing on pivot 17 of lever 14, hammer 10 no longer retained by the catch 15 and under pressure of the helical spring 5, turns to striking position and beats on the striker means 18, 19; at the same time member 8 moving together with hammer 10 goes back to the original position (see Fig. 2), so that the joining point of its triangular slot with the pivot 4 moves from the rear apex to the upper front apex (see Figs. 2 and 4). Rod 6 has a projecting portion passing through a hole provided in the moving breech 30 and in contact with the release catch lever 24 of the automatic extractor 23 for turning catch lever 24 to release the extractor for operation when the gun is opened. In Fig. 7 is partly represented a gun provided with two juxtaposed barrels 31a also provided with the mechanism according to the invention and with two hammers 10, 10a.

The working of the mechanism in this case is similar to that above mentioned; by closing the arm, the pressure of the striking helical spring 5 acts on the left hammer 10, whilst the spring-holder member 1, being driven by the pivot 13, moves back and the pivot 4 moves from the lower front apex to the rear apex of the triangular slotted member 8 (see also Fig. 6), and so on.

What I claim is:

1. In a breech loading firearm, in combination, a rear breech piece; a barrel-carrying breech piece pivotally mounted on said rear breech piece; a tubular member having a closed front end and being slidably mounted in said rear breech piece, said tubular member being connected to said barrel-carrying breech piece for movement with the same; a piston slidable in said tubular member located in the region of the rear end thereof; a spring in said tubular member abutting against said closed end thereof and against said piston; a control member having a slot, said control member having a forwardly located circular lug engaging a corresponding recess in said piston for turnably connecting said control member to said piston, said control member having a rearwardly located circular lug; a hammer pivotally mounted in said rear breech piece for movement between a cocked position and a striking position and having a recess receiving said rearwardly located lug for turnably connecting said hammer and said control member; a sear for holding said hammer in said cocked position and mounted on said rear breech piece; a trigger for releasing said sear; and a transverse pin secured to said tubular member at the rear end thereof and passing through said slot, said pin being located transversely spaced from the axis of said tubular member whereby tilting of said barrel-carrying breech effects forward movement of said tubular member, said pin, and said control member while said spring is compressed by said piston, and said hammer is turned

from said striking position to said cocked position so that said sear locks said hammer, while straightening of said barrel-carrying breech piece effects rearward movement of said tubular member with said pin rearwardly moving in said slot of said control member while said piston is held by said control member and cocked hammer so that said spring is tensioned so that upon release of said hammer by said sear, said hammer is turned by said spring and said control member to said striking position and said control member assumes a position in which said pin is located in a forward portion of said slot.

2. In a breech loading firearm, in combination, a rear breech piece; a barrel-carrying breech piece pivotally mounted on said rear breech piece; a tubular member having a closed front end and being slidably mounted in said rear breech piece, said tubular member being connected to said barrel-carrying breech piece for movement with the same; a piston slidable in said tubular member located in the region of the rear end thereof; a spring in said tubular member abutting against said closed end thereof and against said piston; a control member having a triangular slot, said control member having a forwardly located circular lug engaging a corresponding recess in said piston for turnably connecting said control member to said piston, said control member having a rearwardly located circular lug; a hammer pivotally mounted in said rear breech piece for movement between a cocked position and a striking position and having a recess receiving said rearwardly located lug for turnably connecting said hammer and said control member; a sear for holding said hammer in said cocked position and mounted on said rear breech piece; a trigger for releasing said sear; and a transverse pin secured to said tubular member at the rear end thereof and passing through said triangular slot, said pin being located transversely spaced from the axis of said tubular member whereby tilting of said barrel-carrying breech piece effects forward movement of said tubular member, said pin, and said control member while said spring is compressed by said piston, and said hammer is turned from said striking position to said cocked position so that said sear locks said hammer, with said control member moving in transverse direction so that said pin slides on a forwardly located transverse edge of said triangular slot, while straightening of said

barrel-carrying breech piece effects rearward movement of said tubular member with said pin rearwardly moving in said triangular slot of said control member while said piston is held by said control member and cocked hammer so that said spring is tensioned so that upon release of said hammer by said sear, said hammer is turned by said spring and said control member to said striking position and said control member assumes a position in which said pin is located in a forward portion of said slot.

10 slot.
3. A breech loading firearm as set forth in claim 2 wherein said closed front end of said tubular member has an opening, and including a rod secured to said piston and having a part located in said tubular member, and
15 a projecting part projecting through said opening and toward said barrel-carrying breech piece; and including an extractor device mounted on said barrel-carrying breech piece and actuated by said projecting part of said rod.

4. A firearm as set forth in claim 3 wherein said ex-
20 tractor device includes a catch lever controlled by said
projecting part of said rod.

5. A breech loading firearm as set forth in claim 2 wherein said hammer has a shoulder, and wherein said sear includes a pivoted lever having a point engaging 25 said shoulder in the cocked position of said hammer, a pivot supporting said lever, and a spring abutting on said pivot and said lever and urging the same against said hammer, and wherein said trigger is movable to an actuated position for turning said lever to a position releasing 30 said shoulder.
